UNITED STATES PATENT OFFICE.

VICTORIA TERRY AND EDWARD TERRY, OF BRIXTON, ENGLAND.

SUPPORT FOR VISES.

1,148,130.

Specification of Letters Patent. Patented July 27, 1915.

Application filed April 22, 1914. Serial No. 833,677.

To all whom it may concern:

Be it known that we, VICTORIA TERRY and EDWARD TERRY, subjects of the King of Great Britain, residing at Milton Hall, 117 5 Loughborough Park, Brixton, England, have invented new and useful Improvements in Supports for Vises, of which the following is a specification.

This invention has reference to mountings 10 or supports for vises and the object we have in view is to provide improved means whereby a vise or similar work holding device may be readily moved into and retained in any desired position either upon the top of 15 the work-bench or upon the vertical face or end of said bench thereby facilitating access to the work held by said vise.

In order that our invention may be readily understood and carried into effect by those 20 skilled in the art to which it appertains we will now proceed to describe the same fully for which purpose reference is to be had to the accompanying drawings in which:

Figure 1 represents a plan view of a device 25 embodying this invention. Fig. 2 is a section taken along the line α — α of Fig. 1. Fig. 3 is a view illustrating the vise occupying a position against the vertical front or end of the work-bench.

In the preferred embodiment of the invention we provide a bed plate formed in 30 two parts, 1, 2 and connected by a hinge 3 whereby the parts 2 may be dropped into a vertical position. The bedplate is provided 35 with upstanding edges 4 upon three of its sides the inner walls of said flanges being undercut as seen more clearly at 5 in Fig. 3. The portion 1 of said bed-plate is provided with two longitudinal slots 6, 7 and also 40 with a bolt hole 8 (Fig. 2) whereby it may be pivotally connected to the work bench when desired. A number of bolt holes or recesses 9 and 10 are provided in the portions 1 and 2 respectively of the bedplate for 45 a purpose which will hereinafter appear.

Mounted to slide longitudinally in and revolve upon the aforesaid bed plate is a circular turntable 11 the edge of which is beveled to engage the undercut portions 5 of 50 the flanges 4 thus preventing it from being lifted vertically from the bedplate. The turntable 11 is provided with a spring controlled stud or bolt 12 adapted to take into any of the holes or recesses 9 10 in the bed-

plate when the turntable has been rotated 55 into the desired position.

The vise or other work holding device 13 which may be of any appropriate construction is positively secured to the turntable 11 as for instance by means of the bolts and 60 nuts 14.

The operation of our improved device is as follows: The bedplate 1 is secured to the work-bench either by means of a bolt passed through the bolt hole 8—if it is desired to 65 secure it pivotally to the bench—or by means of bolts passed through the slots 6 and 7 if it is desired to allow of longitudinal movement of the bedplate upon the bench. The vise 13 having been bolted to the circular 70 turntable 11 this latter is engaged in the bed plate by sliding it in from the open end 15 (Fig. 1) the beveled edge of the turntable 11 taking under the overhanging walls 5 of the bedplate. The turntable with the attached vise can now be moved lengthwise of 75 the bedplate or the vise may be caused to occupy any angular position with respect to the bedplate by simply rotating it and the turntable bodily the spring and stud 12 being lifted and then dropped into any one of the recesses 9 in the bedplate thus holding the turntable in the desired position.

It is sometimes necessary or convenient 80 that a vise should be placed vertically that is to say arranged upon the vertical front or end of the bench and this may be readily effected by means of our improved device. The turntable 11 and the attached vise is moved along the bedplate until it abuts 85 against the end wall or flange 4 of the portion 2 of the bedplate. The bedplate is then moved along the bench until the hinge 3 coincides with the end of the bench when the portion 2 of said bedplate is dropped into 90 the position indicated in Fig. 3. The recesses 10 serve a similar purpose to the recesses 9 above described that is to say they are adapted to receive the spring bolt 12 so 95 allowing the vise to be adjusted in any desired angular position. In Figs. 1 and 3 we have indicated in broken lines two of such angular positions of the turntable and vise.

It will be seen that under our invention 100 we have provided a construction which will admit of a vise or cramp being readily moved into any desired position either upon the top 105 of a work bench or upon the vertical front

or ends with a minimum of labor and expenditure of time.

While we have described in the foregoing specification the construction of parts and operations preferred we are aware that numerous changes of construction and operation may be made without departing from the spirit and scope of the invention and we therefore do not wish to be understood as limiting ourselves by the positive terms employed in connection with the description excepting such as the state of the art may require.

What we claim and desire to secure by Letters Patent of the United States is:

1. In vises the combination with a substantially rectangular bed plate in two parts hinged together and having means whereby it may be slidably and rotatably secured to a workbench, a turntable slidably and rotatably mounted in said bed plate a pair of clamping jaws secured to said turntable and means for fixing said turntable and bed plate together in any of several positions of adjustment.

2. In vises a substantially rectangular bed plate in two parts, a hinge connecting said parts together, means in one part of said bed plate for slidably and rotatably securing it to a work bench, a turntable slidably and rotatably mounted in said bed plate, a pair of clamping jaws carried by said turn-

table, and a spring bolt for fixing said turntable and bed plate together in any of several positions of adjustment.

3. In vises a substantially rectangular two part bedplate, hinged together and having upstanding undercut flanges on three of its sides, a circular turntable having its edge beveled to engage said undercut flanges whereby it may be slidably and rotatably engaged with said bedplate, a pair of clamping jaws carried by said turntable means for fixing said turntable and said bed plate together in any of several positions of adjustment and means for slidably and rotatably attaching said bed plate to a work bench.

4. In vises a substantially rectangular bed plate in two parts, a hinge connecting said parts together, means in one part of said bed plate for slidably and rotatably securing it to a work bench, a turntable slidably and rotatably mounted in said bed plate, a pair of clamping jaws carried by said turntable, a spring bolt carried by said turntable and means on both parts of said bed plate co-operating with said spring bolt whereby said turntable and bed plate may be fixed in any of several positions of adjustment.

VICTORIA TERRY.
EDWARD TERRY.
